CLAIM

(52) **U.S. Cl.** **D9/449**; D9/446; D9/452;
D9/447

The ornamental design for a dispensing closure, as shown and described.

(58) **Field of Classification Search** D9/504,
D9/454, 453, 452, 449, 447, 446, 443, 435;
D7/629, 511, 396.2, 392.1; 222/480; 215/220,
215/331, 306, 236, 235; 220/810

DESCRIPTION

See application file for complete search history.

FIG. 1 is a front perspective view of the dispensing closure in accordance with the present invention;

(56) **References Cited**

FIG. 2 is a front view thereof;

U.S. PATENT DOCUMENTS

FIG. 3 is a rear view thereof;
